JOHN M. BROCK, OF NEW YORK, N. Y., ASSIGNOR TO WILLIAM M. CRANE COMPANY,
A CORPORATION OF NEW YORK.

GAS-STOVE.

978,127.

Specification of Letters Patent.

Patented Dec. 6, 1910.

Application filed September 16, 1907. Serial No. 392,994.

To all whom it may concern:

Be it known that I, JOHN M. BROCK, a citizen of the United States, and a resident of New York, county and State of New York, have invented certain new and useful Improvements in Gas-Stoves, of which the following is a specification.

My invention relates to heating and cooking apparatus; and while it may be embodied in constructions adapted for various purposes, it is more particularly applicable to gas stoves and stoves consuming fluid fuel.

Objects of the invention are to provide a novel construction of gas stove which shall contain an incandescent member; which shall in operation be free from objectionable odors and deleterious products of combustion; which shall have its parts effectively and compactly arranged; which shall be economical in construction and operation; and to provide a construction of the character described which shall be neat in appearance and particularly attractive in use. These and other objects of the invention will in part be obvious and in part be more fully explained in the following description.

My invention consists in the novel parts, improvements, combinations and features of construction herein shown and described.

The accompanying drawings, which are referred to herein and form a part hereof, illustrate one embodiment of the invention, the same serving in connection with the description herein to explain the principles thereof.

Of the drawings: Figure 1 is a vertical central section of a gas stove constructed in accordance with certain features of the invention; Fig. 2 is a plan view of the same taken on the line 2—2 of Fig. 1; and Fig. 3 is another plan view of the same taken on the line 3—3 of Fig. 1.

A gas stove constructed in accordance with certain features of my invention comprises in combination a hollow, rigid member forming within itself a combustion chamber and adapted to be heated to incandescence, a burner constructed and arranged to admit air with and independently of the fuel and

to concentrate the combustion substantially within said chamber, and means for protecting the outer surface of said member from drafts of cold air, said means including a casing constructed to admit unheated air to the lower portion and to discharge heated air from the upper portion thereof, said casing being in part at least permeable to light and radiant heat. According to other features of the invention the incandescent member is given an upwardly tapering form; it is vented at its top, the top preferably being open; it is perforated or reticulated; it is formed of a metal adapted to be heated to incandescence, preferably cast iron; it is inclosed within a casing; it is connected with a diaphragm, preferably imperforate, which divides the casing into two compartments or portions, in the upper one of which the incandescent member is located while the burner is located in the other, the lower portion of the casing being constructed to admit unheated air and the upper portion of the casing being constructed to discharge heated air. According to still other features of the invention means are provided for deflecting the heated air on leaving the combustion chamber; the burner is provided with means for mixing air with the fuel supply; and in the top of the stove is located a grill, and at the bottom means for preventing radiation of the heat to the floor. These and other features of the invention will be more fully explained in the following description.

Referring now to the drawings in detail, the embodiment of the invention illustrated comprises an outer shell or jacket 1, which is mounted upon a base 2 having legs 3. At a suitable distance above the base is located a burner 4, having a fuel supply tube 5. Further reference to the burner will be hereinafter made.

An important feature of the invention resides in the provision of means for perfecting and augmenting combustion, thereby serving the two-fold purpose, among others, of greatly increasing the heating efficiency of the apparatus and consuming dangerous gases and eliminating disagreeable odors and other objectionable features

incident to constructions of this character. While this feature may be embodied in various forms and materials, preferably and as shown, there is provided a hollow member 6 forming within itself a combustion chamber, said member being adapted to be heated to incandescence. This incandescent member may be of any suitable material and may be located in any suitable place in the stove. Preferably and as shown, however, said member is formed of metal, sheet or cast, and is situated above the burner where it is subjected to the heated air and products of combustion which pass along its inner surface and heat it to incandescence. By reason of its incandescence said member insures the complete combustion of all combustible gases or vapors.

While the incandescent member may take any suitable shape or be of any desired size to perform said functions, preferably and as shown, it is made in the form of a hollow upwardly tapering member or cone, thereby conforming approximately to the natural shape of the heated gases arising from the burner. To aid in bringing said incandescent member to a state of incandescence, it is perforated to bring about a more intimate contact of the flame and the heated gases with the heated member and also to increase the area of the heated member with which the gases and flame come in contact. In the preferred embodiment, as shown, the member is perforated with numerous perforations throughout the greater part of its area.

The burner 4 may be of any suitable size and form of construction adapted to concentrate the combustion substantially within the chamber formed by the incandescent member so as to heat said member to a low incandescence without the consumption of an undue quantity of fuel. Preferably, and as shown, it is annular in shape and has an outer ring 7 in an inner ring 8 between which parts openings are provided for the admission of air to the combustion chamber independently of the fuel, the burner being preferably interspaced from the incandescent member so as to afford an opening for admission of air between these parts. The outer ring is preferably so situated with respect to the incandescent member and has its outlet openings for the fuel or mixture of fuel and air so arranged that the flames will form a ring and be directed toward the lower inside surface of said combustion chamber so as to apply the heat to the member 6 in an efficient manner. While the inner ring may have its outlets for the fuel disposed in various ways adapted to accomplish the desired result, as shown, they are disposed so that the flames will extend upwardly and outwardly in a direction tending to meet the flames of the outer ring at

points adjacent to the inner surface of the member 6.

It is to be understood that my invention is not limited to the use of gas as a fuel, since the burner may be adapted for the use of oil or various fluid fuels, if desired.

In the preferred form of the invention, and as shown, suitable means are provided for mixing air with the fuel supply, the same consisting of a Bunsen mixing chamber 9, 75 preferably situated without the casing adjacent to the base thereof.

Another important feature of the invention resides in the provision of means for maintaining perfect combustion. If the heated air is allowed unduly to remain in the combustion chamber, the intake of fresh air to support combustion is prevented, and carbon monoxide is given off. To obviate this defect, provision is made for the free 85 passage of the heated air from the combustion chamber. While this may be accomplished in any suitable way, preferably and as shown, a vent of any desired size is provided, preferably, in the top of the combustion chamber. The heated air passing through this vent and through the perforations in the walls of the combustion chamber, a strong draft is secured and atmospheric air enters through spaces between the inner 95 and outer rings 7 and 8 of the burner. By passing through the walls of flame on the said rings such of the air as is not taken to support combustion in the said walls of flame enters the combustion chamber in a 100 superheated condition, thereby facilitating the consumption of any combustible gases or vapors with which it unites in the chamber formed by the incandescent member. In order that the draft may not become excessive and permit the heated products of combustion to pass out of the combustion chamber before perfect combustion has taken place, suitable means are provided for regulating the draft, the same, in the preferred form of the invention and as shown, taking the form of a deflector which serves to deflect downwardly the heated air issuing from the combustion chamber. This deflector is preferably located above the combustion chamber, being situated at any suitable distance from the same and being of any suitable shape. Preferably and as shown, a dome-shaped deflector 10 is provided, the same being preferably held in 110 place by being fastened to the member 6 by means of lugs 11. An additional deflector 12 is also provided in the preferred embodiment of the invention, the same preferably being also dome-shaped and located above 115 the first deflector and being preferably suspended from the top of the outer shell 1 by hangers 13. This deflector preferably extends over the entire area embraced within the outer shell 1. If desired, one only of the 120

130

deflectors may be used, preferably the deflector 10.

One important function performed by the deflectors in connection with the incandescent member is the radiation of the heat near the floor, where it is most needed. The deflectors not only make it possible to keep the member 6 in an incandescent state so that the heat will be radiated but they serve to prevent the upward radiation and at the same time cause the heated gases to leave the stove in a lateral direction instead of rising rapidly to the upper part of the room in accordance with their natural tendency.

15 An important feature of the invention consists in providing means for preventing the cold air which enters the stove at the burner from rising into the chamber formed by and between the outer shell 1 and the outer surface of the chamber 6. While this may be accomplished in any suitable way, for instance by so shaping said incandescent member that its lower edge will extend outwardly to the shell 1, preferably and as shown, an imperforate flange or diaphragm 14 is provided, the same extending from the combustion chamber at a point preferably below where the flame impinges on said chamber to the outer shell and thus dividing 30 said shell 1 into two compartments. Said flange is, preferably and as shown, fastened to the outer shell and also affords means for supporting in position the member 6, in the preferred embodiment illustrated being 35 made an integral part thereof.

Another important feature of the invention consists in providing means whereby a view may be had of the incandescent member 6, which, when in a state of incandescence, presents a strikingly attractive and cheerful appearance. This may be done in any suitable way, as, for example, by making suitable apertures or perforations in the shell. It will also be seen that the outer shell or jacket 1 may be made in a variety of forms and shapes in which the incandescent member may be displayed and protected from excessive drafts of cold air and which forms and shapes may be so designed 50 as to add greatly to the attractiveness and cheerfulness of the stove, especially when in use.

In the embodiment of the invention illustrated in the drawings the shell is shown as being cylindrical in form and perforated, the perforations preferably extending throughout the entire extent of the shell. The perforations and apertures serve the further purpose of providing a passage for 55 the heat radiated from the member 6 and the heated air in the upper compartment into the surrounding atmosphere. The perforations in the outer shell 1, extending below the diaphragm 14, will also permit the passage of air to the lower compartment of the

stove, where it will support combustion in the flames of the rings 7 and 8 of the burner, from whence it will be drawn upwardly between the rings of the burner and maintain combustion, as heretofore explained.

70

To prevent radiation of heat downwardly, a suitable bottom is provided for the stove, the same, preferably and as shown, consisting of metal plates 15 and 16, between which is a layer of asbestos 17 or similar material. 75 The stove is also provided with a removable top 18, the same preferably and as shown consisting of two sections, in the lower of which sections is contained a grill 19 for cooking, the upper section 20 preferably being ornamental in character.

75

While the various parts of the stove may be held together in any suitable way, in the embodiment illustrated two rods 21 extend through the stove near the shell, being secured at the top and bottom.

85

It will be seen that by reason of the construction shown and described a form of gas stove is provided which is simple and compact, neat and cheerful in appearance economical in construction and operation, whose parts are easily duplicated, and which is adapted for the use of other fluid fuels.

90

Advantages other than those heretofore set forth will be apparent to those skilled in the art.

95

It is to be understood that my invention in its broader aspects is not limited to the precise construction shown nor to any particular construction by which the invention 100 has been or may be carried into effect, as many changes may be made in the details of the parts without departing from the main principles of the invention and without sacrificing its chief advantages.

105

I claim:

1. A gas stove comprising in combination, a hollow, rigid member forming within itself a combustion chamber and adapted to be heated to incandescence, a burner constructed and arranged to admit air with and independently of the fuel and to concentrate the combustion substantially within said chamber, and means for protecting the outer surface of said member from drafts of cold air, said means including a casing constructed to admit unheated air to the lower portion and to discharge heated air from the upper portion thereof, said casing being in part at least permeable to light and radiant heat.

110

2. A gas stove comprising in combination, an upwardly tapering, hollow, reticulated, rigid member forming within itself a combustion chamber and adapted to be heated to incandescence, a burner constructed and arranged to admit air with and independently of the fuel and to concentrate the combustion substantially within said chamber, and a casing for protecting the outer sur-

115

120

125

130

face of the said member from drafts of cold air, said casing being constructed to admit unheated air to the lower portion and to discharge heated air from the upper portion thereof and being in part at least permeable to light and radiant heat.

3. A gas stove comprising in combination, an upwardly tapering, hollow member formed of cast iron and forming within itself a combustion chamber, a burner constructed and arranged to admit air with and independently of the fuel and to concentrate the combustion substantially within said chamber, and a casing for protecting the outer surface of said member from drafts of cold air, said casing being constructed to admit unheated air to the lower portion and to discharge heated air from the upper portion thereof and being in part at least permeable to light and radiant heat.

4. A gas stove comprising in combination, an upwardly tapering, hollow, reticulated, rigid, metallic member forming within itself a combustion chamber and adapted to be heated to incandescence, a burner constructed and arranged to concentrate the combustion substantially within said chamber, a deflector mounted on the top of said member and a casing inclosing said parts, said casing being in part at least permeable to air, light and radiant heat.

5. A gas stove comprising in combination, an open-topped, hollow member forming within itself a combustion chamber and adapted to be heated to incandescence, a burner constructed and arranged to concentrate the combustion substantially within said chamber, a deflector mounted immediately above the open top of said member, and a casing inclosing said parts, said casing being in part at least permeable to light and radiant heat.

6. A gas stove comprising in combination, an upwardly tapering, open-topped, hollow, reticulated member forming within itself a combustion chamber and adapted to be heated to incandescence, a burner constructed and arranged to concentrate the combustion substantially within said chamber, a deflector mounted immediately above the open top of said member, and a reticulated casing inclosing said parts.

7. A gas stove comprising in combination, a hollow member forming within itself a combustion chamber and adapted to be heated to incandescence, a burner constructed and arranged to admit air with and independently of the fuel and to concentrate the combustion substantially within said chamber, a casing for protecting the outer surface of said member from drafts of cold air, said casing being constructed to admit unheated air to the lower portion and to discharge heated air from the upper portion thereof and being in part at least permeable to light

and radiant heat, and a deflector arranged above said member and extending substantially throughout the horizontal area of said casing.

8. A gas stove comprising in combination, an upwardly tapering, open-topped, hollow, rigid member forming within itself a combustion chamber and adapted to be heated to incandescence, a burner constructed and arranged to concentrate the combustion substantially within said chamber, a deflector mounted immediately above the open top of said member, a reticulated casing inclosing said parts, and a second deflector arranged above said first-named deflector and extending substantially throughout the horizontal area of said casing.

9. A gas stove comprising in combination, a hollow, rigid member constructed and arranged to form within itself a combustion chamber and adapted to be heated to incandescence, a burner constructed and arranged to admit air with and independently of the fuel and to concentrate the combustion substantially within said hollow member, a diaphragm extending outwardly from said hollow member and a casing inclosing said parts and constructed to admit unheated air to said burner beneath said diaphragm and discharge the heated gases above said hollow member.

10. A gas stove comprising in combination, a hollow member forming within itself a combustion chamber and having an open top and bottom, said member being adapted to be heated to incandescence, a burner arranged near the bottom of said member and constructed to concentrate the combustion substantially within said chamber, a diaphragm extending outwardly from the bottom of said member, a deflector mounted above the open top of said member, and a casing inclosing said parts, said casing being in part at least permeable to air, light and radiant heat.

11. A gas stove comprising in combination, a hollow, reticulated member forming within itself a combustion chamber and adapted to be heated to incandescence, a Bunsen burner arranged near the base of said member and having flame-distributing and air inlet openings whereby said member may be uniformly heated from the interior to incandescence, and a casing inclosing said parts and having openings near the bottom for the admission of unheated air to said burner and openings near the top for the escape of light, radiant heat and heated air.

12. A gas stove comprising a shell, an upwardly tapering, hollow, reticulated member forming a combustion chamber inclosed in part at least by said shell, a burner arranged to heat said member from the interior to incandescence, a diaphragm below said member, a deflector above said member,

a top having a removable portion and a grill, means for permitting an ingress of air to the combustion chamber, means for mixing air with the fuel supply, and a bottom adapted to prevent downward radiation of heat.

5 In testimony whereof, I have signed my

name to this specification, in the presence of two subscribing witnesses.
